BENZOTHIADIAZINE-1,1-DIOXIDES

Lincoln Harvey Werner, Summit, and George de Stevens, New Providence, N.J., assignors to Ciba Corporation, a corporation of Delaware
No Drawing. Filed July 12, 1961, Ser. No. 123,417
5 Claims. (Cl. 260—243)

The present invention concerns 3-cycloalkyl-lower alkyl-1,2,4-benzothiadiazine-1,1-dioxides. More particularly, it relates to compounds having one of the formulae

and

in which the letter *n* stands for one of the whole numbers 1, 2, 3 and 4, *R*₁ represents cycloalkyl having from three to eight carbon atoms as ring members, and *R*₂ stands for hydrogen, halogeno, lower alkyl, trifluoromethyl and nitro, or salts of such compounds, as well as process for the preparation thereof.

The letter *n* stands primarily for 1, but may also represent one of the numbers 2, 3 and 4. The group of the formula $-(C_nH_{2n})-$ may, therefore, represent lower alkylene having from one to four carbon atoms, primarily methylene, as well as 1,1-ethylene, 1,2-ethylene, 1,1-propylene, 1,2-propylene, 2,2-propylene, 2,3-propylene, 1,3-propylene, 1,1-butylene, 1,4-butylene and the like.

The cycloalkyl portion *R*₁ has from three to eight, preferably from five to six, ring carbon atoms and is represented primarily by cyclopentyl and cyclohexyl, as well as by cyclopropyl, cyclobutyl, cycloheptyl and cyclooctyl. These cycloalkyl radicals are preferably unsubstituted, but may also have as substituents lower alkyl, e.g. methyl, ethyl, isopropyl and the like, attached to ring carbon atoms, and represent, for example, 2-methyl-cyclopentyl, 3-methyl-cyclopentyl, 3-ethyl-cyclopentyl, 3-isopropyl-cyclopentyl, 4-methyl-cyclohexyl, 4-ethyl-cyclohexyl and the like.

The cycloalkyl-lower alkyl radical having the formula $-(C_nH_{2n})-R_1$ may, therefore, be represented primarily by cycloalkylmethyl, in which cycloalkyl has from three to eight, preferably from five to six, ring carbon atoms, e.g. cyclopentylmethyl or cyclohexylmethyl, as well as cyclopropylmethyl, cyclobutylmethyl, cycloheptylmethyl, cyclooctylmethyl and the like, as well as 1-cycloalkylmethyl, in which cycloalkyl has from three to eight, particularly from five to six, ring carbon atoms, e.g. 1-cyclopentylethyl, 1-cyclohexylethyl, 1-cycloheptylethyl and the like, 2-cycloalkylethyl, in which cycloalkyl has from three to eight, particularly from five to six, ring carbon atoms, e.g. 2-cyclopropylethyl, 2-cyclobutylethyl, 2-cyclopentylethyl, 2-cyclohexylethyl, 2-cycloheptylethyl and the like, or other cycloalkyl-lower alkyl radicals, in which cycloalkyl has from three to eight, particularly from five to six, ring carbon atoms and lower alkyl contains from three to four carbon atoms, e.g. 1-cyclopentylpropyl, 2-cyclopentylpropyl, 3-cyclopentylpropyl, 4-cyclopentylbutyl, 1-cyclohexylpropyl, 2-cyclohexylpropyl, 3-cyclohexylpropyl, 4-cyclohexylbutyl and the like.

2

The group *R*₂, which is preferably attached to the 6-position or the 7-position of the 1,2,4-benzothiadiazine-1,1-dioxide nucleus, may represent hydrogen, nitro or lower alkyl having from one to four carbon atoms, e.g. methyl, ethyl, n-propyl, isopropyl, n-butyl, secondary butyl, tertiary butyl and the like. However, *R*₂ represents primarily trifluoromethyl or halogeno, especially halogeno having an atomic weight between 35 and 80, i.e. chloro or bromo, as well as fluoro and the like.

10 Salts of the compounds of this invention are primarily alkali metal, e.g. sodium, potassium and the like, or alkaline earth metal, e.g. magnesium, calcium and the like, salts thereof.

15 The compounds of this invention counteract the effect of physiological pressure agents, such as epinephrine, norepinephrine and hypertensive polypeptides, e.g. angiotensin-II-amide and the like, and thus cause a lowering of the blood pressure. They can, therefore, be used as antihypertensive agents to relieve hypertensive conditions, 20 such as renal hypertension, essential hypertension, malignant hypertension and the like.

Particularly useful are the compounds having one of the formulae

25 or

30 in which the letter *m* stands for one of the numbers 0 and 1, and one of the groups *R*₂' and *R*₂'' represents chloro, bromo or trifluoromethyl, and the other stands for hydrogen, or the alkali metal, e.g. sodium, potassium and the like, salts thereof.

35 The new compounds of this invention may be used in the form of pharmaceutical preparations, which contain the new 3-cycloalkyl-lower alkyl-1,2,4-benzothiadiazine-1,1-dioxides or salts thereof in admixture with a pharmaceutical organic or inorganic, solid or liquid carrier suitable for enteral or parenteral administration. For making up the preparations there can be employed substances which do not react with the new compounds, such as water, gelatine, lactose, starches, stearic acid, magnesium stearate, stearyl alcohol, talc, vegetable oils, benzyl alcohols, gums, waxes, propylene glycol, polyalkylene glycols or any other known carrier used for pharmaceutical preparations. The latter may be in solid form, for example, as capsules, tablets, dragees and the like or in liquid form, for example, as solutions, suspensions, emulsions and the like. If necessary, these compositions may contain auxiliary substances, such as preserving, stabilizing, wetting, emulsifying agents and the like, as well as salts for varying the osmotic pressure, buffers, etc. They may also contain, in combination, other useful substances, particularly antihypertensive agents, such as Rauwolfa alkaloids, e.g. reserpine, deserpidine, rescinnamine and the like, semi-synthetic Rauwolfa alkaloids, e.g. syrosingopine and the like, veratrum alkaloids, e.g. protoveratrine A, protoveratrine B and the like, synthetic antihypertensive drugs, e.g. hydralazine, dihydralazine, guanethidine and the like, ganglionic blockers, e.g. chlorisondamine and the like, or any other useful substances, such as potassium chloride and the like.

40 The compounds of this invention are prepared according to methods known per se, for example, by cyclizing a

2-sulfamyl-N-(cycloalkyl-lower alkanoyl)-aniline, particularly a compound of the formula

or a 2-(N-acyl-sulfamyl)-N-(cycloalkyl-lower alkanoyl)-aniline, particularly a compound of the formula

in which n , R_1 and R_2 have the previously-given meaning, and acyl, particularly the acyl radical of the formula Ac , stands for the acyl radical of an organic carboxylic acid, to form the desired 3-(cycloalkyl-lower alkyl)-1,2,4-benzothiadiazine-1,1-dioxide compound, particularly a compound having one of the formulae

or

in which n , R_1 and R_2 have the previously-given meaning, and, if desired, converting a resulting salt into the free compound, and/or, if desired, converting a resulting compound into a salt thereof.

The acyl radical of an organic carboxylic acid, which substitutes the sulfamyl group, and which is represented in the above formula by the radical Ac , is the acyl radical of a cycloalkyl-lower alkanoyl acid and has more especially the formula $-CO-(CnH2n)-R_1$, in which n and R_1 have the previously-given meaning. However, it may also stand for any other suitable acyl radical of an organic carboxylic acid, such as a lower alkanoyl acid, e.g. acetic, propionic acid and the like.

Cyclization of the 2-sulfamyl-N-(cycloalkyl-lower alkanoyl)-aniline is carried out at an elevated temperature, preferably at a temperature between 75° and 200° . The cyclization may take place in the absence or in the presence of an inert solvent, such as, for example, ethanol, propanol, diethyleneglycol dimethyl-ether, dimethylformamide and the like, if necessary, in a closed vessel under pressure, and/or in the atmosphere of an inert gas, e.g. nitrogen and the like.

The starting material used in the above procedure is new and is intended to be included within the scope of this invention. Particularly useful as starting materials are the compounds of the formula

in which m , R_2' and R_2'' have the previously-given meaning.

The starting materials may be prepared, for example, by reacting a 2-sulfamyl-aniline, especially a compound of the formula

5 or a 2-(N-acyl-sulfamyl)-aniline, particularly a compound of the formula

10

in which R_2 and Ac have the previously-given meaning, with the halide, particularly chloride, or the anhydride of a cycloalkyl-lower alkanic acid, particularly an acid 15 of the formula $HOOC-(CnH2n)-R_1$, in which n and R_1 have the previously-given meaning. The acylation of the sulfamyl-nitrogen may take place simultaneously with the desired acylation of the aniline-nitrogen. Whenever the treatment with the acylating reagent is carried 20 out in the presence of an inert, slightly polar to non-polar organic solvent, such as an aromatic hydrocarbon, an ether and the like, the mono-acylated product, in which the aniline-nitrogen is acylated, is obtained. Any generated acid may be neutralized by adding a suitable reagent, e.g. sodium acetate and the like. Diacylation occurs whenever the acylation reagent is used in an excess amount and in the presence of a base, such as a tertiary amine, e.g. N,N,N -triethylamine and the like, or a heterocyclic base, e.g. pyridine and the like.

25 30 The compounds of this invention may also be prepared by reacting a 2-sulfamyl-aniline compound, particularly a compound of the formula

35

in which R_2 has the previously-given meaning, with an 40 ortho-ester, especially a lower alkyl ortho-ester, of a cycloalkyl-lower alkanic acid, particularly an ortho-ester of the formula

45

in which n and R_1 have the previously-given meaning, and R represents lower alkyl, and, if desired, carrying out the optional steps.

As mentioned hereinbefore, an ortho-ester of a cycloalkyl-lower alkanic acid is preferably a lower alkyl ortho-ester, in which lower alkyl (represented in the above formula by R) has from one to four carbon atoms and stands for methyl, ethyl, n-propyl, isopropyl, n-butyl and the like; ethyl ortho-esters are the preferred reagents. The 55 above reaction is preferably carried out at an elevated temperature, and in the presence of an inert organic solvent; if necessary, it may be performed in a closed vessel under pressure, and/or in the atmosphere of an inert gas, e.g. nitrogen and the like.

60 The resulting product may be obtained in the form of the free compound or as a salt thereof. A resulting metal, such as an alkali metal, salt may be converted into the free compound by treatment with an acidic reagent, such as an aqueous mineral acid, e.g. hydrochloric, sulfuric acid and the like.

65 A resulting free compound may be converted into a metal, particularly into an alkali metal salt, for example, by treatment with an alkali metal hydroxide, e.g. sodium hydroxide, potassium hydroxide and the like, in the presence of a suitable inert solvent, such as in a lower alkanol, e.g. methanol, ethanol and the like, or in water and evaporating the solvent, or by reacting the free compound, for example, in an ether, e.g. p-dioxane, diethyleneglycol dimethyl-ether and the like, solution, with a metal, particularly an alkali metal, hydride or a metal, particularly an alkali metal, amide,

70

75

5

in which the letter *m* stands for an integer from 0 to 1, 10 both inclusive, one of the groups R_2' and R_2'' represents a member selected from the group consisting of chloro, bromo and trifluoromethyl and the other stands for hydrogen.

4. 7 - chloro - 3 - cyclopentylmethyl - 1,2,4 - benzo- 15 thiadiazine - 1,1 - dioxide.

5. 6 - chloro - 3 - cyclopentylmethyl - 1,2,4 - benzo- thiadiazine - 1,1 - dioxide.
